UNITED STATES PATENT OFFICE.

FOREST H. HARTZELL, OF DAYTON, OHIO.

COMMUTATOR FOR ELECTRIC MOTORS.

1,410,914.

Specification of Letters Patent. Patented Mar. 28, 1922.

Application filed October 23, 1917. Serial No. 198,107.

To all whom it may concern:

Be it known that I, FOREST H. HARTZELL, citizen of the United States, residing at Dayton, in the county of Montgomery and State of Ohio, have invented certain new and useful Improvements in Commutators for Electric Motors, of which the following is a specification.

My invention relates to electric motors and more particularly to an economically constructed form of commutator therefor. While the commutator forming the subject matter hereof is particularly adapted for toy motors or small motors of low efficiency, it is to be understood that it is not limited to such use but the same mode of construction suitably modified as to proportion and relation of parts may be employed for larger motors or those of higher efficiency.

20 The object of the invention is to improve the structure of commutators whereby they will not only be cheapened in construction, but light motors for toy purposes will be more efficient in operation, economical in manufacture, easily and quickly assembled, and unlikely to become short circuited or out of repair.

With the above primary and other incidental objects in view as will more fully appear in the specification, the invention consists of the features of construction, the parts and combinations thereof, and the mode of operation, or their equivalents, as hereinafter described and set forth in the claims.

Referring to the drawings, Fig. 1 is a perspective view of the assembled motor commutator which forms the subject matter hereof. Fig. 2 is a transverse sectional view. Fig. 3 is a longitudinal sectional view on line 3-3 of Fig. 2. Fig. 4 is a plan view of the blank from which a contact is formed. Fig. 5 is a perspective view of the commutator contact formed from the blank shown in Fig. 4. Fig. 6 is an end elevation of an assembled commutator embodying a modification of the construction shown in the preceding figures.

Like parts are indicated by similar characters of reference throughout the several views.

In constructing the commutator there is employed a main body of insulating material which may consist of fiber, hard rubber, bakelite or other phenolic condensation product, or some similar material of non-electro-

conductive material. This insulating body 1 may be formed integral or as a single continuous body but is preferably though not necessarily laminated or formed of a series 60 of disks 2 arranged side by side and in contact one with the other in sufficient number to build up the insulating body 1 of required extent. One advantage of constructing the insulating body of a series of disks or laminae 65 2 of such material as fiber or composition is that they may be formed by a stamping operation in a punch press. Such method of manufacture is extremely cheap and rapid. The disks 2 are formed with a central hole 70 or opening 3 to receive the armature shaft and a second series of small holes 4 arranged in spaced relation and upon the periphery are formed a series of spaced teeth or tongues 5. Inasmuch as the disks 2 are 75 all identical in size and arrangement of the openings and tongues, the openings 4 and tongues or teeth 5 register with those of the succeeding disks when assembled to form the insulating body 1. Positioned about the 80 periphery of the insulating body 1 and separated by the tongues or teeth 5 are segmental contact plates 6 formed from sheet metal the blank being shaped as shown in Fig. 4. As there shown the plate 6 is provided with oppositely disposed projecting fingers or tines 7 and also with a projecting tongue or finger 8 for the attachment of the armature windings. The blank shown in Fig. 4 in practice is shaped as indicated in the 85 detail view Fig. 5. The armature winding connection 8 is bent upward to a position angular in relation with the plate 6 while the tines or fingers 7 are bent downward in the opposite direction. The plate itself is 90 curved upon a radius to agree with the periphery of the insulating body 1. In assembling the device the plates 6 with their downturned tines or fingers 7 and upturned armature connection 8 are positioned about 95 100 the insulating body 1 intermediate the succeeding rows of teeth or tongues 5. It will be understood that if the insulating body 1 is formed as an integral body instead of a series of laminae or disks a series of longitudinally disposed ribs or beads upon the periphery of said integral body will correspond to the succession or row of registered teeth or tongues 5.

The plates 6 having been assembled about 110 the periphery of the body 1 intermediate such rows of teeth or tongues 5, the down-

turned tines or fingers 7 thereof will extend in registry with the holes or openings 4. By means of a suitable staking or bending fixture or tool the ends of the fingers or tines 7 are inturned and clenched within the holes 4 of the disks or the body 1 as shown in detail in Fig. 3. In Fig. 5 these fingers or tines have also been shown inturned in their final form. In Fig. 6 there has been shown a modification of the construction heretofore described in which in lieu of tongues or teeth 5 upon the disks 2 or ribs or beads formed upon an integral insulating body 1, such disks or integral insulating body are formed with a series of longitudinal grooves or slots 9. Bars or strips of insulating material such as mica, fiber, hard rubber or other suitable non-conductive material are inserted within the slots 9 intermediate the succession of contact plates 6. After the assembly has been completed the surface of the commutator is turned or ground off, thereby equalizing the teeth or ribs 5 or the inserted insulating bars or strips 10 with the surfaces of the adjacent plates 6.

While the commutator illustrated in the drawing has been shown provided with but six contact surfaces, it will be understood that any number of such contacts may be employed, either more or less than those shown in the drawings. The construction heretofore described provides a commutator of simple, economical and efficient construction for the purpose for which it is designed.

From the above description it will be apparent that there is thus provided a device of the character described, possessing the particular features of advantage before enumerated as desirable but which obviously is susceptible of modification in its form, proportion, detail construction or arrangement of parts, without departing from the principle involved or sacrificing any of its advantages.

While in order to comply with the statutes, the invention has been described in language more or less specific as to certain structural features, it is to be understood that the invention is not limited to any specific details, but that the means and construction herein described comprise but one mode of putting the invention into effect, and the invention is therefore claimed broadly in

any of its possible forms or modifications within the scope of the appended claims.

Having thus described my invention, I claim:

1. In a commutator of the character described, a core comprising a plurality of toothed discs arranged side by side, and a series of contact plates longitudinally disposed about the periphery of the core and insulated one from another by the projection of the peripheral teeth of the discs between the plates, the discs being held in assembled relation and the contact plates in engagement therewith by clenching the ends of the plates over the terminal discs.

2. A peripheral face commutator, comprising a core, a plurality of contact plates arranged about the periphery of the core, and intermediate projections of insulation integral with the core upon the contact face of the commutator intermediate the contact plates, the ends of said plates being clenched upon the opposite ends of the core.

3. A commutator of the character described, a cylindrical body of insulating material peripherally grooved to form integral ribs of insulation upon the contact face of the commutator, contact plates located about the peripheral face of the cylindrical body intermediate said integral ribs, the ends of said plates being clenched over the ends of the body.

4. A commutator of the character described comprising a series of discs of insulating material placed side by side, and a series of contact plates longitudinally arranged in spaced relation about the periphery of the discs and having their ends inturned to hold the discs in assembled relation.

5. A commutator of the character described, including a core, comprising a series of discs arranged side by side and a series of contacts arranged about the periphery of the core and holding the discs in assembled relation.

In testimony whereof, I have hereunto set my hand this 17th day of October, A. D. 1917.

FOREST H. HARTZELL.
